(57) **CLAIM**

The ornamental design for a WOM-45° sheet pile connecting element, as shown and described.

DESCRIPTION

FIG. 1 is a perspective view of the connecting element for sheet piles according to my design. The connecting element is shown broken away in the middle to indicate the connector has no specific length; and,

FIG. 2 a front view of the connecting element of FIG. 1.

The design relates to a connector to be welded on a sheet pile wall component as interlock for other sheet pile components, wherein the connector varies in its axial length depending from its intended use.
